(57) **CLAIM**

I claim the ornamental design for the in-tire sensor, as shown.

DESCRIPTION

FIG. 1 is a front perspective view of an in-tire pressure and condition sensor showing my new design;

FIG. 2 is a back perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

In the drawings, the broken line showing of environmental association matter is for illustrative purposes only and forms no part of the claimed design.
